UNITED STATES PATENT OFFICE

91,224

DESIGN FOR A CASING FOR WEIGHING SCALES

William Watling, Chicago, Ill., assignor to
Watling Scale Company, Chicago, Ill., a cor-
poration of Illinois

Application September 30, 1933. Serial No. 49,388

Term of patent 14 years

To all whom it may concern:

Be it known that I, WILLIAM WATLING, a citizen of the United States, residing in Chicago, county of Cook, and State of Illinois, have invented a new, original, and ornamental Design for a Casing for Weighing Scales, of which the following is a specification, reference being had to the accompanying drawing forming a part thereof.

In the drawing:

Fig. 1 is a perspective view of a casing for weighing scales showing my new design, and
Fig. 2 is a side elevation thereof.

I claim:

The ornamental design for a casing for weighing scales substantially as shown.

WILLIAM WATLING.
